US00D923586S

(12) **United States Design Patent** (10) **Patent No.:** **US D923,586 S**
(45) **Date of Patent:** **** Jun. 29, 2021**

(54) **TERMINAL BLOCK**

- (71) Applicant: **OMRON Corporation**, Kyoto (JP)
- (72) Inventors: **Tadahiko Ogawa**, Moriyama (JP); **Aiki Kora**, Kyoto (JP); **Takashi Sakaguchi**, Takatsuki (JP); **Yuki Kuniyasu**, Kusatsu (JP)
- (73) Assignee: **OMRON Corporation**, Kyoto (JP)
- (**) Term: **15 Years**
- (21) Appl. No.: **29/690,268**
- (22) Filed: **May 7, 2019**

(30) **Foreign Application Priority Data**

Dec. 17, 2018 (JP) 2018-027491
Dec. 17, 2018 (JP) 2018-027492
Dec. 17, 2018 (JP) 2018-027493

(57) **CLAIM**

The ornamental design for a terminal block, as shown and described.

DESCRIPTION

FIG. 1 is a front, top, and right side perspective view of a terminal block showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines in the figures show portions of the terminal block that form no part of the claimed design.

1 Claim, 7 Drawing Sheets
